UNITED STATES PATENT OFFICE

ALFRED G. HEGGEM, OF TULSA, OKLAHOMA

PACKING CASING HEAD

Application filed March 12, 1930. Serial No. 435,078.

This invention relates to a packing casing head for oil wells providing means for suspending strings of casing in concentric relation and for preventing blow-outs by controlling gas pressure which may occur between adjacent strings of casing.

The principal object of the invention is to afford an efficient packing casing head of simple form which may be easily assembled. A further object of the invention is to produce a device of the character indicated in which it is not necessary to employ tongs for effecting the assembly of the external casing head members.

Another object of the invention is to provide effective means for packing joints between the gas outlets with which the casing head members are respectively provided.

In the drawings illustrating the invention, the scope whereof is pointed out in the claims:

Figure 1 is a side elevational view of a packing casing head embodying the invention as employed for the suspension of a plurality of strings of casing, showing also the relation of a tubing head thereto.

Figure 2 is a vertical central section of the construction shown in Figure 1.

Figure 3 is a side elevational view of a modified form of packing casing head involving the invention.

Figure 4 is a vertical central section of the form of packing casing head illustrated in Figure 3.

In the drawings, 1 indicates a flange member which is screw threaded on its interior, as at 2, to enable it to be screwed on to the upper threaded end of the outer string of well casing 3. This bottom flange 1 is usually installed in a cellar beneath the derrick floor of the oil well and may be supported in any well known or desired manner. It is formed with an upwardly facing surface 4 constituting a seat for the packing head member 5 immediately above it and is provided with an upwardly projecting marginal collar 6 serving to center the head. The surface of the flange member 1 beneath the superimposed packing head 5 is circularly grooved or recessed, as at 7, to receive a packing ring 8 of rubber or other suitable material

sealing the joint beneath the flange member 1 and the adjacent packing head member 5. The packing recess 7 is preferably located at the junction of the upstanding collar 6 and the upwardly facing interior surface 4 of the flange member 1, both because of convenience of manufacture and effectiveness. As a means for securing the packing head member 5 in assembled relation to the flange 1, the upstanding collar of the latter may advantageously be formed with a series of threaded radial openings which receive correspondingly threaded studs or set screws 9. The inner ends of these set screws by cooperating with the conical or bevelled exterior surface 10 of the packing head serve to secure the head to the flange and to force it firmly downward against the underlying packing ring 8.

The packing head member 5 is of general ring-like form. It is provided with one or more fluid outlet passages 11 communicating with the interior of the packing head, suitable pipes 12 being threaded into said outlet openings and valves (not shown) being installed in the pipes for controlling the flow of fluid in the usual manner.

Upon its interior and above the inner ends of the outlet passages 11, the packing head is formed with an upwardly facing annular shoulder 13 which is preferably bevelled so as to incline downwardly toward the longitudinal axis of the head. This shoulder provides a seat for a correspondingly bevelled metallic ring 14 which is split so that it may be placed in position after the casing is connected up. The recessed interior surface 15 of the packing head above the upwardly facing annular shoulder 13 also receives another split ring of metal 16 whose upper face is bevelled so as to incline downwardly and inwardly. Between these split follower rings a packing ring 17 of rubber or other suitable material is interposed. On its underside the packing head is fashioned with a downwardly opening recess 18 for receiving the upper end of a casing collar 19 between which and the under surface of the packing head 5 a suitable packing 20, such as rubber, is interposed, the rubber packing preferably being positioned in an annular groove 21 into which

the upper end of the neighboring casing collar 19 projects. As shown in the drawings, the outer wall 22 of the recess 18 of the packing head preferably flares downwardly somewhat so as to facilitate the entry of the upper end of the cooperating casing collar 19. At its lower end the packing head 5 is preferably formed with an exterior bevelled or conical surface 10 for cooperating with the set screws 9.

The upper surface of the packing head is provided with an annular seat or surface 23 which underlies the opposed packing head above it. Encircling this annular surface and projecting upwardly above it is a circular collar 24 carrying a series of threaded set screws 9 which serve to secure adjacent packing head members in assembled relation in the same manner that set screws 9 heretofore described serve to secure the lowermost packing head member 5 to the flange member 1 which is mounted upon the outer casing. To provide means for anchoring the packing casing heads each head member 5 is preferably fashioned with oppositely arranged projecting anchor lugs 25 which may be conveniently formed as grooved bosses or spools through which the fluid outlet passages 11 extend. Anchor bolts 26 pass around the anchor lugs and are suitably secured at their lower ends. It will be understood that these anchor bolts may cooperate with the top packing head member 5, thus anchoring the device as a whole, or they may cooperate with the lower head member, as shown in the drawings, or with any or all of the other casing head members as may be desired.

Associated with each packing head member 5 is a casing collar 19 which is provided on its interior with tapering threads after the fashion of the collar customarily used for connecting sections of casing. This collar is screwed upon the immediately adjacent inner string of casing 27, 28 or 29 as the case may be. Near its upper end it is provided with an external downwardly facing annular shoulder 42 for cooperating with the split ring 16 that is immediately above the packing 17, said shoulder, as in the case of the ring 16, preferably being bevelled so as to taper downwardly. The collar is formed with an upwardly extending annular portion 30 adapted to enter the downwardly opening packing recess or groove 21 in the under surface of the superimposed packing head member 5. As shown in the drawings, the upper end of this annular flange portion 30 of the casing collar may advantageously be bevelled or inclined in opposite directions so as not only to facilitate its entry into the packing recess 21 but also to effectively force the packing 20 into intimate contact with the walls of said recess. It will be understood that the number of casing head members 5 and casing collars 6 that are employed varies

with the number of strings of casing. At its upper end the device is provided with means for holding down the inner string of casing, such means preferably being formed as a top fitting or cap 31 through which the inner string of casing passes and which is provided at its base with a tapering or conical surface 32 with which the set screws 9 carried by the adjacent casing head member 5 cooperate to maintain the cap member 31 securely in place. The top member 31 fits telescopically over the upper end of the adjacent casing collar 19. As the packing heads, casing collars, split ring followers, packings and connecting set screws are the same in form and function and differ only in size in accordance with the diameter of the casing, these parts and their details of construction have been identified throughout the drawings by corresponding reference numerals.

For the purpose of showing its relation thereto the packing casing head has been illustrated in association with a tubing head having a body 33 provided with pipes 34 permitting the outflow of oil from the space between the inner casing 29 and the tubing 35. Secured to the upper end of the body 33 by set screws 36 is a spider 37 within which are slips 38 for clamping the tubing. The joint between the body 33 and spider 37 is sealed by suitable packing 39, while a follower 40 which is adjustably secured to the spider by set screws 41 serves to compress packing material between said follower and the underlying slips. In setting the packing casing head, the lower flange 1 is screwed on to the upper end of the outer string of casing 3 and the lowermost packing head 5 is seated thereon and secured thereto by means of the cooperating set screws 9 carried by the flange member. The casing collar 19 which is to be secured to the upper end of the immediately adjacent inner string of casing 27 is then screwed on to the lower end of a joint or section of casing of appropriate diameter, which serves as an elevator joint and by which the collar 19 is lowered and screwed onto the upper end of the casing 27. It is then raised above the encircling packing head 5 until its downwardly facing external shoulder 42 is above the upper surface of the adjacent head member 5, after which the split ring 14 is dropped on to the interior shoulder 13 of the head member and the rubber packing ring 17 and the adjacent upper split ring 16 are placed in position. As these rings are split they may be brought into assembled position after the casing is connected up. The string of casing 27 is then lowered and its weight, acting through the shoulder 42, causes the packing 17 to be compressed between the follower rings 14 and 16, thus forming a fluid type joint between the casing collar 19 and the encircling packing head member 5. The elevator joint is then backed off from its screw 130

threaded engagement with the casing collar 19, and the next head member 5 is lowered into place, being secured to the member 5 below it by the set screws 9 which, by cooperating with the exterior bevelled face 10 of the upper head member serve to force the latter downwardly so as to compress the packing 20, thus forming a fluid tight joint between the upper end of the casing collar 19 and the packing head member next above it. This process is repeated as often as is necessary, depending upon the number of strings of casing, each packing head 5 which is put in place serving, by its weight, to increase the effectiveness of the packings at the joints between the casing collars and the packing heads 5. When the uppermost casing collar 19 has been put in position the top fitting or cover flange 31 is placed thereon and secured to the upper casing head member 5 by means of the set screws 9. The cover flange or top cap 31 thus prevents the inner string of casing 29 from rising, tying it to the entire set of casing heads. By this means the outer strings of casing lend their strength in resisting the blowing out of the inner string of casing.

In the modified form of the invention illustrated in Figures 3 and 4, the component sections or heads are secured together by bolts 43 instead of by means of the set screws 9 as heretofore described. Except for this difference and slight changes in the form of parts, the modified form of the invention is similar to that illustrated in Figures 1 and 2 of the drawings and, therefore, requires but brief description. The lower flange member 44 which is screwed on to the upper end of the outer string of casing 3 is provided with a series of openings 45 for the bolts and is suitably recessed, as at 46, to receive the heads of the latter, the seats for said bolt heads being preferably bevelled or inclined, as indicated at 66, to permit the bolts to converge or incline upwardly toward the longitudinal axis of the device. For the purpose of sealing the joint between the lower flange member 44 and the packing head member 47 immediately above it, the flange member may advantageously be formed at the top with an upwardly protecting annular collar 48 extending into a downwardly opening groove or recess 49 in the under surface of the adjacent head member, a packing ring 50 of rubber or other suitable material being positioned in the recess above the upwardly projecting collar.

Each of the packing head members 47 is formed with gas outlets 51 which are threaded for suitable pipe connections; and each head member is also fashioned with oppositely disposed anchor lugs 52 for operating with anchor bolts 53 corresponding to the anchor bolts whose purpose has been here-

tofore explained. To enable the head members 47 to be readily handled and raised and lowered by means of hooks and chains and the like, each head member may advantageously be provided above the anchor lugs 52 with oppositely disposed downwardly extending hooked lugs 54. The lugs 52 and 54 are preferably disposed midway between the gas outlets 51.

On its interior each of the packing head members 47 is formed with an upwardly facing shoulder 55 which is preferably bevelled. This shoulder forms a seat for a correspondingly bevelled split metal ring 56 between which and an upper split metal ring 57, a rubber packing ring 58 is interposed.

The shouldered casing collars 59 preferably correspond in form and function to the casing collars 19 employed in the form of the device already described, each resting upon the split follower ring 57 that is immediately below it and projecting at its upper end into the packing recess 49 in the under surface of the superposed casing head member 47. A rubber ring 60 or other suitable packing material disposed in the recess 49 packs the joint between the upper end of the casing collar and the packing head member 47 next above it.

The top fitting or cover flange member 61 which encircles the innermost string of casing and transversely overlaps the end of the uppermost casing collar 59 is provided with a flange 62 having holes 45 therein suitably spaced for receiving the bolts 43, the upper surface of the flange adjacent the bolt holes being inclined to form seats for the nuts 63. Each of the head members 47 is likewise preferably provided at its upper end with an inclined or dished marginal flange 64 through openings in which the bolts 43 extend. If desired, a packing ring 65 of rubber or other suitable material may be interposed between the cover flange member 61 and the casing collar 59 mounted on the innermost string of casing. The manner of assembling the form of the device illustrated in Figures 3 and 4 is similar to that heretofore described.

A packing casing head constructed in accordance with the invention has the advantages of simplicity, readiness of attachment and effectiveness of result. The necessity for employing tongs to tighten the casing head members is avoided as no screw threads are employed in connecting the heads to the casing; and there are but two packing joints to each head member, one above the gas outlet and one below it.

I claim:

1. A casing head for oil wells embodying a head member having an opening therethrough and a fluid escape outlet communicating with said opening, means adapted to be mounted upon an outer string of cas-

ing for supporting said head member, a casing collar projecting into said opening and threaded for connection with an inner string of casing, means extending over the upper end of said collar for normally preventing upward movement of the latter with respect to said head member, means for retaining said last named means in assembled relation to the head member, and a plurality of packing means one of which is interposed between the casing collar and said head member and one of which is interposed between the casing collar and said means for preventing upward movement of the latter.

2. A casing head for oil wells embodying a plurality of head members each having an opening therethrough and a fluid escape outlet communicating therewith, said head members being arranged one above another, a plurality of casing collars each threaded upon its interior for connection with a corresponding string of casing, said collars respectively projecting into said openings of the head members and being so formed that they may be slid into said openings from above, a plurality of packing means respectively interposed between one of said casing collars and successive head members adjacent thereto, and means for maintaining said head members in assembled relation.

3. A casing head for oil wells embodying an integral head member having an opening therethrough for receiving a casing collar and having a fluid escape outlet communicating with said opening, said head member being provided with an interior shoulder, means adapted to be mounted upon a string of casing for supporting said head member, a casing collar projecting into said opening and threaded for connection with a string of casing, said collar being provided between its ends with an exterior shoulder which radially overlaps said interior shoulder of the head, and means including a split ring interposed between said shoulders for supporting said casing collar on said head member, said split ring being disposed within said opening of the head member and substantially conforming to said opening.

4. A casing head for oil wells embodying an integral head member having an opening therethrough for receiving a casing collar and having a fluid escape outlet communicating with said opening, said head member being provided with an interior bevelled shoulder, means adapted to be mounted upon an outer string of casing for supporting said head member, means for maintaining said head member in assembled relation to said supporting means, a casing collar projecting into said opening and threaded for connection with an inner string of casing, said collar being provided between its ends with an exterior downwardly facing bevelled shoulder and being so formed that it may be

slid into said opening from above, a plurality of bevelled split packing rings, one of said rings cooperating with the bevelled shoulder on said head member and the other cooperating with the bevelled shoulder of said casing collar, and packing means interposed between said rings.

5. A casing head for oil wells embodying a head member having an opening therethrough and a fluid escape outlet communicating with said opening and having upon its under side a recess adapted to receive the upper end of a casing collar, a casing collar projecting into said opening and threaded interiorly for connection with a string of casing and projecting at its upper end into said recess, means for maintaining said collar in said recess, means for supporting said head member, and means for maintaining said head member in assembled relation to said supporting means.

6. A casing head for oil wells embodying a head member having an opening therethrough for receiving a casing collar and having a fluid escape outlet communicating with said opening and provided with an outwardly projecting anchor lug through which said fluid outlet extends, means adapted to be mounted upon an outer string of casing for supporting said head member, a casing collar projecting into said opening and threaded interiorly for connection with an inner string of casing, means for supporting said casing collar on said head member, means for securing said head member in assembled position, and means for normally preventing upward movement of said casing collar with respect to said head member.

7. A casing head for oil wells embodying a lower flange member adapted to be mounted upon an outer string of casing, an upper flange member, one or more head members interposed between said lower flange member and said upper flange member, one or more casing collars arranged between said lower flange member and said upper flange member, means for maintaining said flange members and heads and collars in assembled relation, each of said head members having an opening therethrough for receiving a casing collar and having a fluid escape outlet communicating with said opening and provided with an interior shoulder, each of said casing collars projecting into the said opening of an adjacent head member and being so formed that it may be slid into said opening from above and being interiorly threaded for connection with an inner string of casing and being provided with an exterior shoulder, a plurality of split rings respectively engaging said shoulders, and packing means interposed between said split rings.

8. A casing head for oil wells, said head involving means for supporting a string of

casing including a member having an opening therethrough for receiving a collar which is interiorly threaded for connection with a string of casing, a head member provided 5 upon its under-side with a recess adapted to receive the upper end of said collar, said first named member being provided with an upwardly facing shoulder and said collar being formed between its ends with a downwardly 10 facing shoulder spaced upwardly from said upwardly facing shoulder, means interposed between said shoulders for supporting said collar on said first named member, and means for maintaining said collar in said recess of 15 the head member.

In testimony whereof I affix my signature.
ALFRED G. HEGGEM.
